US00D793131S

(12) **United States Design Patent** (10) **Patent No.:** **US D793,131 S**
(45) **Date of Patent:** ** *Aug. 1, 2017

(54) **STAND APPARATUS FOR INFLATABLES**

(71) Applicant: **Doron Gazit**, North Hollywood, CA (US)

(72) Inventor: **Doron Gazit**, North Hollywood, CA (US)

(73) Assignee: **AIR DIMENSIONAL DESIGN, INC.**, North Hollywood, CA (US)

(*) Notice: This patent is subject to a terminal disclaimer.

(**) Term: **14 Years**

(21) Appl. No.: **29/513,631**

(22) Filed: **Jan. 2, 2015**

Related U.S. Application Data

(63) Continuation-in-part of application No. 29/513,627, filed on Jan. 2, 2015, which is a continuation-in-part of application No. 29/513,629, filed on Jan. 2, 2015.

(57) **CLAIM**

The ornamental design for a stand apparatus for inflatables, as shown and described.

DESCRIPTION

FIG. 1 is a perspective view of my new design for a stand apparatus for inflatables;

FIG. 2 is a first side elevational view thereof;

FIG. 3 is a second side elevational view thereof;

FIG. 4 is a third side elevational view thereof;

FIG. 5 is a fourth side elevational view thereof;

FIG. 6 is a top view thereof; and,

FIG. 7 is a bottom view thereof.

The broken lines shown in the drawing views are included for the purpose of showing environmental structure that forms no part of the claimed design.

1 Claim, 7 Drawing Sheets
